UNITED STATES PATENT OFFICE.

JOHN MANNING VAN HEUSEN, OF JAMAICA PLAIN, MASSACHUSETTS.

BOUND COLLAR.

1,267,291.

Specification of Letters Patent. Patented May 21, 1918.

Application filed January 22, 1916. Serial No. 73,525.

To all whom it may concern:

Be it known that I, JOHN MANNING VAN HEUSEN, a citizen of the United States, residing at Jamaica Plain, Suffolk county, State of Massachusetts, have invented certain new and useful Improvements in Bound Collars; and I do hereby declare the following to be a full, clear, and exact description of the invention, such as will enable others skilled in the art to which it appertains to make and use the same.

This invention relates to soft seamless collars of the folded or turned-down type, provided with a binding around its edges.

In the production of soft folding collars from seamless fabric, and particularly from a multiply fabric, which is folded to form the outer turned-down portion, this turned-down portion and the end tabs of the collar form abrupt angles with each other. Upon applying a continuous binding to the collar, it has been found that the binding extends a sufficient distance from the collar, at this abrupt angle, to form an uneven and unsightly projection when the collar is folded for use. According to the present invention, this objectionable feature is overcome and the collar is provided with a binding which is continuous from the folded portion to the tab, and which will nevertheless be taken up and held in a smooth and even manner at the angle formed by the turned-down portion and tab, when the collar is folded.

The invention is illustrated by the accompanying drawings, in which—

Figure 1 represents a collar of the turned-down type, embodying the invention;

Fig. 2 shows one end of the collar unfolded;

Fig. 3 shows one end of the collar folded;

Fig. 4 is an enlarged detail view, with parts in section, illustrating the invention; and

Fig. 5 is a vertical sectional view of the central portion of the collar of Fig. 4.

The invention is illustrated as applied to a seamless multiply fabric, the material of which is sufficiently stiff to maintain the shape of the collar without the employment of starch, while nevertheless sufficiently pliable to assume the necessary curvature to fit the neck of the wearer without undue rigidity.

The collar illustrated is made up of the inside panel or band portion 1 having at its ends the tabs 2 formed as extensions of the

inside band, and having therein the usual button holes 3. The outer turned-down portion 4, in the usual collar construction, forms with the end tab 2 a right-angle or abrupt angle 6, similar to a right-angle. A binding 5 is shown as applied to the collar and as extending from the turned-down portion to the tab in a continuous manner. If the collar is cut from a single piece of fabric, of the desired shape, and is then bound, the binding will, when the collar is folded, form a loose projecting portion at the abrupt angle formed by the end tab and the outer folding portion. According to the present invention, in order to overcome this objection, the collar is provided with a V-shaped notch 7 at such angle, and the binding material, when applied to the collar, enters this notch, so that the binding is taken up and held thereby when the collar is folded for use. While the notch 7 is hardly perceptible, nevertheless it is sufficient to permit the binder foot, such as is ordinarily attached to sewing machines, to get in and around the corner and fasten the binding in the desired manner. Instead of making the notch 7 in the form of a V, it will of course be understood that other suitable forms of notches (not shown) can be used which will enable the same result to be accomplished. The V-shaped notch is particularly adapted for this purpose.

Where the fabric is a multiply fabric, it may with advantage be provided with a weakened portion where it is folded. Such a weakened fold is shown at 8, and may be made as shown in Fig. 5 by omitting some of the threads of one or more of the inner plies of the fabric. Where such a weakened portion is provided at the fold, the V-shaped notch is preferably formed near the inner edge thereof, with the result that the collar, although having the binding taken up and somewhat gathered at said corner, is not of materially increased thickness at this point.

I claim:

1. A folding collar having an outer folding portion and an end tab portion forming an abrupt angle with each other, and having a notch in the fabric at said angle, and an edge binding for the tab and outer folding portion inclosing the edge of the tab and folding portion and arranged to be taken up by said notch when the collar is folded; substantially as described.

2. A folding collar of multiply fabric having an outer folding portion and an end tab portion forming an abrupt angle with each other, said collar having a weakened portion at its fold and having a notch in said weakened portion at said angle, and a binding for the tab and outer folding portion arranged to be taken up by said notch when the collar is folded; substantially as described.
- 10 3. A folding collar of multiply fabric of a weave sufficiently stiff to maintain the shape of the collar without the employment of starch and having an outer folding or

turn-down portion and an end tab portion forming an abrupt angle with each other, 15 and having a recess or notch in the fabric at said angle, said collar being provided with a fold portion of increased flexibility, and an edge binding for the tab and outer folding portion inclosing the edge of the 20 tab and folding portion, and arranged to be taken up by said recess or notch when the collar is folded; substantially as described.

In testimony whereof I affix my signature.

JOHN MANNING VAN HEUSEN.
